United States Patent Office

Des. 190,794
Patented July 4, 1961

190,794

PILLOW

Arthur H. Anson, 805 N. 26th St., Allentown, Pa.

Filed Mar. 31, 1960, Ser. No. 59,970

Term of patent 14 years

(Cl. D3—9)

Fig. 1.

Fig. 2.

I claim:

The ornamental design for pillow, as shown.
